UNITED STATES PATENT OFFICE.

HOWARD A. TONGUETT, OF MARION, OHIO, ASSIGNOR OF ONE-HALF TO JUSTICE H. UNCAPHER, OF MARION, OHIO.

CURTAIN-POLE BRACKET.

1,375,617.

Specification of Letters Patent. Patented Apr. 19, 1921.

Application filed July 15, 1919. Serial No. 310,944.

To all whom it may concern:

Be it known that I, HOWARD A. TONGUETT, a citizen of the United States, residing at Marion, in the county of Marion and State 5 of Ohio, have invented certain new and useful Improvements in Curtain-Pole Brackets; and I do hereby declare the following to be a full, clear, and exact description of the invention, such as will enable others 10 skilled in the art to which it appertains to make and use the same.

The invention relates to improvements in curtain poles and more particularly to the supports therefor.

15 An important object of this invention is to provide a curtain pole having a novel form of bracket by which the curtain pole may be quickly and securely attached thereto.

20 A further object of this invention is to provide a curtain pole and bracket which is simple to apply, of highly simplified construction and cheap to manufacture.

25 A further object of this invention is to provide a curtain pole bracket which may be attached to the side of a window frame without marring the front of the same.

Other objects and advantages of the invention will be apparent during the course 25 of the following description.

30 In the accompanying drawing forming a part of this application, and in which like numerals are employed to designate like parts throughout the same,

Figure 1 is a plan view of a window curtain pole and bracket embodied in the invention, the same illustrating the application 35 of the invention,

Fig. 2 is a side elevation, showing a portion of the pole in section, and

40 Fig. 3 is a perspective of the bracket.

In the drawings wherein for the purpose 45 of illustration is shown a preferred embodiment of the invention, the numeral 5 designates a curtain pole adapted to be arranged

50 transversely of a window frame 6. The end portions of the poles are curved inwardly as indicated at 7 for engaging a pair of brackets generally designated by the numeral 8. The pole or support 5 is sub-

stantially ellipsoidal in cross section and has 55 one side 9 open. The bracket 8 includes an attaching plate 10 having openings 11 for the reception of screws or other suitable fastening devices adapted for attaching the bracket to a window frame. A body plate

12 is connected to the attaching plate 10 by an outwardly offset connecting plate 13. A forwardly curved and upwardly extending tongue 14 is formed integral with the body plate 12 and has its upper end terminating 60 below the horizontal plane of the upper side of the body plate 12. An L-shaped locking member 15 is extended from the body plate 12 at its upper side and is provided with a downwardly extending locking arm 16. 65 The extension 14 and the locking member 15 form a socket 17 for the reception of the curved end portion 7 of the curtain pole. An opening 18 is provided in the top of the end portions of the curtain pole and is 70 adapted to receive the downwardly extending locking arm 16 of the L-shaped member 15. The upper end of the curved extension 14 is adapted to engage the inner side 75 of the end portion of the curtain pole and adapted for supporting the same. The terminals of the curved portions of the brackets abut the inner side of the horizontal portion of the locking member 15. As the upper end of the curved extension 14 is 80 disposed approximately horizontally with the inner side of the horizontal arm of the locking member 15, the curtain rod is supported horizontally. A shoulder 19 is provided at the bottom of the body plate 12 and 85 is adapted to be engaged by the lower portion of the terminal of the pole.

As illustrated in Fig. 2, the downwardly extended arm 16 has its inner side inclined inwardly from its lower end as indicated at 90 20, to prevent the accidental displacement of the curtain pole.

In applying the improved curtain pole bracket it will be apparent that the end portions are inserted within the sockets 17 and 95 the downwardly extended arm placed within the recesses 18 thereby locking the pole in position and effectively retaining the same against accidental displacement.

While I have shown and described the 100 preferred embodiment of my invention, it is understood that such minor changes in arrangement and construction of parts may be made as will remain within the spirit of the invention and the scope of the appended 105 claims.

Having thus described the invention, what is claimed is:

1. The combination with a curtain pole of substantially ellipsoidal form in cross 110

section and having one side open and its ends turned, of a body plate adapted to be secured to a window frame and having an offset portion provided with a horizontal 5 arm extended from its upper edge and terminating in a downwardly directed locking arm having an inclined inner face and adapted to extend through an opening in the upper edge of the turned end of the 10 pole, said body plate having a forwardly and upwardly curved supporting arm beneath the first mentioned arm and adapted to extend into the end of the curtain pole and engage the under face of the upper 15 side thereof to support said pole on said body plate, the body plate having a stop shoulder to receive the end of the lower wall of said turned end of the pole.

2. As a new article of manufacture, a 20 curtain pole bracket formed of a single blank and comprising a body plate having an offset portion adapted to be secured to a window frame, a central forwardly ex-

tended and upwardly curved supporting arm projecting from the outer edge of said body plate for engagement in the end of a curtain pole to support the same, an upper locking arm extended parallel with the main portion of the central arm and terminating in a downwardly extended locking end for engagement through an opening in the upper face of the curtain pole supported on the first mentioned arm, the locking end having a beveled inner wall, and a stop shoulder formed beneath the first mentioned arm to receive the end of the lower wall of the curtain pole and retain the curtain pole against movement on the first mentioned arm and the locking arm of the bracket. 25 30 35 40

In testimony whereof I affix my signature in presence of two witnesses.

HOWARD A. TONGUETT.

Witnesses:

GRACE I. TETTIE,
C. S. LIPPINCOTT.
